UNITED STATES PATENT OFFICE.

DANIEL L. BRAINE, OF NEW YORK, N. Y., ASSIGNOR TO COMPOSITE TIE-PLATE CORPORATION, OF NEW YORK, N. Y., A CORPORATION OF NEW YORK.

TIE-PLATE.

1,076,812.

Specification of Letters Patent.

Patented Oct. 28, 1913.

Application filed October 24, 1912. Serial No. 727,536.

To all whom it may concern:

Be it known that I, DANIEL L. BRAINE, a citizen of the United States, residing at New York, in the county of New York and State 5 of New York, have invented certain new and useful Improvements in Tie-Plates, of which the following is a specification.

This invention relates to improvements in rail supporting devices commonly termed 10 tie-plates, and has for its principal object the providing of an improved form of rail-supporting device which is economical to manufacture and efficient in operation.

Another object is the providing of an im- 15 proved device of the class described to be interposed between the base of a railway rail and tie or other similar support, which may be readily placed, or replaced without necessitating movement of the rail.

20 Still another object is the providing of a rail-supporting device which will hold the rail firmly to the correct gage and in desired position as well as to permit of uninterrupted "wave" motion of the track rail, 25 without however permitting lateral movement thereof.

Still another object is to provide, in connection with such a device, a replaceable 30 wearing block, carried by the main block, which will receive most of the wear due to the supporting of the rail, and which may be constructed of relatively stronger or tougher material.

Other objects will be made apparent and 35 set forth in the following specification and accompanying drawings, in which—

Figure 1 is a side elevation of my device showing the rail in section. Fig. 2 is a plan view of the construction shown in Fig. 40 1. Fig. 3 is an end elevation. Fig. 4 is a transverse section, taken along the line 4—4 of Fig. 2, showing the fastening spikes in elevation; and Fig. 5 is a perspective view, showing my device proper in disassembled 45 relation.

Like numerals and letters refer to like elements throughout the drawings.

As illustrated, A designates a conventional form of rail having a flanged base 10 50 indirectly carried upon the usual form of tie, or similar support B. My device comprises a metal frame C and preferably a compound wooden block D. The metal frame is provided with parallel downwardly 55 extending sides 15, which extend between

top members 16, the latter being suitably placed apart a distance equal to the width of and so as to fit or embrace the lateral edges of the base of the rail. The side members of the frame are preferably cut out between the top portions 16, as indicated by the numerals 17.

Located in each of the top portions are the drive spike apertures 18, preferably diagonally opposed, as indicated in Fig. 5, and having one side opening into the space between the top portions. These drive spike apertures have their peripheries outwardly notched, as indicated at 19. Each of the top portions is also provided with circular screw spike 70 apertures 20, slightly dished-out, as indicated by the numerals 21, which also open into the space between the top portions 16 and are diagonally opposed. The periphery of each of the apertures 20, is, however, of sufficient extent to prevent lateral movement of a screw spike when inserted therein.

The main block D is adapted to be inserted between the sides of the metal frame, which closely fits on said block. It will be 80 apparent that any lateral movement of the metal frame with respect to the block will be impossible. The block D is also provided with spiking apertures 22, adapted to register with corresponding apertures in the frame C, as shown in Fig. 5. This block is provided with a cut-out portion 23 corresponding to the space between the top portion of the frame and somewhat greater in depth, in which a wearing block E is arranged, as shown in Fig. 4 of the drawings. This wearing block is preferably of such thickness that its upper surface lies some distance below the surface of the top or cross members of the metal frame and yet 95 be contacted, retained and held in position by the side members of said frame when in assembled relation, as will be apparent from an examination of the drawings. This block E is preferably constructed of wood of considerably greater strength and wearing quality than the block D.

In the use of my improved device, the base of the rail is supported directly by the wearing block E, and is carried in the space between the top members of the metal frame and the sides of the cut-out portion of block D, as shown most clearly in Figs. 1 and 4 of the drawings. Railway spikes 25 are driven through the apertures 18 and corre- 110

sponding apertures 22 into the body of the tie, or other main support, B. These spikes are preferably constructed with outwardly extending upper corners 26, which fit into and engage notches 19 in the periphery of the apertures 18, thus preventing lateral movement of the upper part of said spikes and also preventing contact of the body of the spike with the lateral edge of the rail base, as well as minimizing the danger of the bending of the spike heads backwardly. Screw spikes 27 are inserted through the apertures 20 and corresponding apertures 22 and are fastened into the body of the tie or support B, as shown in Fig. 4. The under sides of the heads 28 of the screw spikes are adapted to rest in dished-out portions 21 of the top portions of the frame, and the periphery of the aperture is so constructed as to prevent contact between the body of the spike and the lateral edge of the rail base.

It will be apparent that as shown in the drawings the metal frame is entirely out of contact with the tie, and that any pressure brought upon such tie must be transmitted through the wooden block D. It is obvious, therefore, that cutting and crushing of the tie, as well as the use of the usual tie-plate, will be eliminated. Furthermore, the location and use of the wearing block E directly below the rail will operate to cause any wearing and crushing to be borne thereby. These wearing blocks may be readily replaced at slight expense and trouble, without necessitating the replacement of the wooden blocks D.

The side thrust of the rail base will be taken care of by the sides 23' of the cut-out portion of block D, and also by the inner edges of the top or cross members of the metal frame. It is also to be noted that the metal frame is constructed of such thickness preferably as to prevent direct contact of the lower surfaces of the heads of the spikes with the upper surface of the rail base A, thus permitting uninterrupted wave motion—both vertically and longitudinally—of the rail. It will be apparent that any thrust of the rail base against the heads of the spikes will be taken care of by the top portion of the metal frame. Inasmuch as the lower surface of the wearing block E comes below the upper surface of the cut-out portion of the sides of the metal frame, accidental displacement of the wearing blocks will be also prevented.

The design and construction of my improved metal frame are such as to permit of their being, and it is my intention to make the same of sheet iron, rolled or pressed into shape, with the cut-out portion and spike perforation punched by suitable machinery.

While I have described and shown my improved device with more or less particular-

ity, I do not wish to be unduly restricted to such showing and description beyond the scope of the appended claims.

What I claim is:

1. In a device of the class described, a main wooden block, and a non-metal wearing block fitted and operatively supported therein, said main block being adapted to be secured on a tie or sleeper and directly support a railway rail. 75

2. In a device of the class described, a main wooden block, and a relatively harder non-metal wearing block fitted and supported therein and adapted to directly support a railway rail and be carried by said main wooden block, said main block being adapted to be directly supported on and secured to a tie or sleeper. 80

3. In a device of the class described, a main wooden block centrally recessed, and a relatively harder non-metal wearing block fitting and mounted in said recess to support a railway track rail, said main block being adapted to be directly supported on and secured to a tie or sleeper. 85

4. In a device of the class described, a main wooden block, a metal frame adapted to be mounted on said wooden block, and a wearing block fitted within and carried by said wooden block. 90

5. In a device of the class described, a metal frame provided with spaced apart top members and downwardly depending side members extending between said top portions, and a wooden block adapted to be carried between the sides of said frame, the sides of said frame and block being recessed or cut-away between said top portions to receive a track rail. 95 100

6. In a device of the class described, a metal frame provided with spaced apart top members and downwardly depending side members extending between said top members, a main wooden block adapted to be carried between the sides of said frame, the sides of said metal frame and block being recessed or cut-away between said top members to receive a track rail, and a relatively harder wearing block fitted within and carried in said cut-away portion of the main block. 110 115

7. In a device of the class described, a metal frame provided with spaced apart top members and downwardly depending side members extending between said top members, a main wooden block adapted to be carried between the sides of said frame, the side members of said frame and block being recessed or cut-away between the top members to receive a track rail, and a wearing block fitting and carried in said cut-away portion of said main block, the wearing block being located so that its upper surface will lie below the top members of said metal frame and be held in operative 120 125 130

position by the side members of the metal frame.

8. In a device of the class described, a main wooden block, a sheet steel frame mounted on said wooden block and provided with spaced apart top members and side members extending between said top members, the said side members being partially cut-away between said top members, said main block being cut away between said top members to receive a track rail, the upper surface of the cut-out por-

tion of said wooden block being located below the upper surface of the cut-out portions of the sides of said metal frame, and 15 a wearing block fitted in the cut-out portion of the main block.

In testimony whereof, I have subscribed my name.

DANIEL L. BRAINE.
